CLAIM

The ornamental design for a tissue processing bag clamp, as shown and described.

DESCRIPTION

FIG. 1 is a top view of a tissue processing bag clamp; FIG. 2 is a bottom view thereof; FIG. 3 is a top, right side and front perspective view thereof; FIG. 4 is a top, left side and rear perspective view thereof; FIG. 5 is a top, right side and rear perspective view thereof; FIG. 6 is a front view thereof; FIG. 7 is a right side view thereof; FIG. 8 is a rear view thereof; and, FIG. 9 is a left side view thereof.

The dash lines in the drawings depict portions of the tissue processing bag clamp that form no part of the claimed design.
